UNITED STATES PATENT OFFICE.

IANTHAS J. ROLFE, OF SPRINGVILLE, UTAH.

REVERSING MECHANISM FOR DISPLAY APPARATUS.

1,233,920.

Specification of Letters Patent. Patented July 17, 1917.

Application filed December 4, 1915. Serial No. 65,093.

To all whom it may concern:

Be it known that I, IANTHAS J. ROLFE, a citizen of the United States, residing at Springville, in the county of Utah and State of Utah, have invented new and useful Improvements in Reversing Mechanism for Display Apparatus, of which the following is a specification.

This invention relates to reversing mechanism for display apparatus especially designed for use in displaying advertising or other signs, in such a manner as to bring a series of signs successively into view at a display opening and maintain each sign in display position for a predetermined period.

The object of the invention is to provide novel mechanism for shifting the signs or sign carrier frames embodying a reciprocating carriage provided with dogs to engage and transfer motion to said signs or sign carrier frames, and adapted to be operated by mechanism reversible by the action of the carriage itself to shift the carriage for travel in opposite directions, the construction being such that the driving mechanism may be operated by a small electric or other motor, so that the device may be employed for window display purposes when desired.

The invention consists of the features of construction, combination and arrangement of parts herein fully described and claimed, reference being had to the accompanying drawings in which:

Figure 1 is a front elevation of a display apparatus embodying my invention.

Fig. 2 is a sectional plan view on the line 2-2 of Fig. 1.

Fig. 3 is a front elevation with the front wall of the casing removed.

Fig. 4 is a rear elevation with the rear section of the casing removed.

Fig. 5 is a sectional plan view on the line 5-5 of Fig. 3.

Figs. 6 and 7 are vertical longitudinal sections showing the carriage at the limits of its movements.

Fig. 8 is a sectional plan view showing in full and dotted lines the clutch and locking devices shifted to their different positions.

Fig. 9 is a vertical front to rear section on the line 8-8 of Fig. 7.

Fig. 10 is a bottom plan view of the carriage.

In carrying my invention into practice,

I provide a suitable frame or casing 1, shown in the present instance as including a body portion 2, a detachable front wall 3, and a detachable rear section 4, said front 60 wall and rear section being secured in position by screws or other suitable fastenings and readily removable for installing the working parts of the apparatus and for repairs and renewal of parts as occasion 65 may require. At one end of the casing the front wall 3 is provided with an observation or display opening 5, which opening communicates with a display chamber or compartment 6 arranged at one end of the 70 body of the casing, said chamber having as its counterpart a return chamber or compartment 7 at the opposite end of the body of the casing, said chambers or compartments being separated by a partition strip 75 8. The partition strip 8 is of less width than the depth of the compartments, so as to coöperate with the front wall 3 and suitable rear guide strips 9 to form front and rear guideways 10 and 11 extending between the compartments.

The chambers or compartments 6 and 7 are separated from a base compartment 12 by a horizontal partition 13, forming the bottom wall of said compartments and said 85 guideways and the top wall of the base chamber 12. Secured to the rear wall of the chamber 6 are longitudinally extending bowed springs 14, and secured to the front wall of the chamber 7 are similar springs 90 15, which springs serve a purpose herein-after fully described.

Arranged within the casing is a series of signs or sign carrier frames 16 of oblong rectangular form being shown in the 95 present instance, which frames are designed to receive interchangeable sign display cards or pictures. These frames are movable between the two compartments 6 and 7, and are designed to be fed from a stack in the return or magazine compartment 7, through the rear guideway to the rear of the stack in the front compartment 6, and to be successively shifted from compartment to compartment, the foremost frame 100 of the stack in the display compartment being displayed through the opening 5 for a predetermined period and then returned through the front guideway to the magazine compartment and ready to be again shifted through the same orbit of movement, as 105 will be readily understood. The springs 14 110

within the compartment 6 are provided for moving the stack therein forwardly to bring the front frame of the stack into display position and in the front guideway, 5 while the springs 15 within the compartment 7 are provided to press the stack of frames therein rearwardly so that the rear-most frame of the stack will be disposed within the rear guideway ready to be moved 10 forward to the rear of the display compartment. On the movement of a frame in the compartment 6 to display position, which occurs upon the transfer of a frame from the stack within the compartment 7 15 to the stack within the compartment 6 the frame so displayed will be kept in line with the observation opening for a predetermined period, say ten or more seconds, during which the operating mechanism is 20 in action to bring up another sign frame from the magazine compartment to the display compartment.

The mechanism for shifting the signs or sign carrier frames comprises a reciprocating carriage 17 provided with wheels or rollers 18 to run upon a pair of spaced bracket rails 19 in the compartment 12, said carriage being provided with a central longitudinally extending rack bar 20 meshing 25 with a pinion 21, whereby it is adapted to be driven. The carriage carries at its opposite ends gravity feed dogs 22 and 23, each provided with a weighted arm 24 whereby it is normally held projected and 30 may be retracted under pressure. The respective dogs 22 and 23 are arranged at opposite ends and opposite sides of the carriage, and each dog is provided with a shoulder or abutment surface 25 and a rearwardly extending and beveled guide lip 26 leading thereto. On the beginning of the feed motion of the carriage the abutment surface of the dog 22 engages the rear end 35 of the rear carrier frame of the stack in the compartment 7 and slides the same forwardly through the rear guideway to the rear of the stack in the compartment 6, said frame being brought into contact with the springs 14 and becoming a part of the stack 40 in the chamber 6, while on the backward or return motion of the carriage the abutment surface of the dog 23 engages the rear end 45 of the front carrier frame of the stack in the compartment 6, which has been previously displayed, and slides the same through the front guideway into the compartment 7. As the frames are removed 50 from each compartment and carried into the other compartment, it will be evident that 55 the sets of springs 14 and 15 will engage the same and keep the frames pressed into stack form, the springs 14 feeding the frames forward in the compartment 6, while the springs 15 feed the frames rearward in the 60 compartment 7. As each dog travels inac-

tively on its return motion it engages and rides over the adjacent outer carrier frame and its beveled lip at the limit of its movement comes into engagement with and snaps behind the rear edge of the carrier frame to 70 which it is to transfer motion, as will be readily understood, such construction of the abutment surfaces and beveled lips preventing the dogs from binding or hanging against the display frames, as will be understood. 75

The mechanism for actuating and reversing the motion of the carriage comprises, in addition to the rack bar 20 and pinion 21, a transmission shaft 27 to which said pinion is fixed, and which is adapted to be revolved in opposite directions by a pair of transmission sprocket wheels 28 and 29, which are loosely mounted on said shaft. These sprocket wheels 28 and 29 are provided with clutch members 28' and 29', arranged in spaced relation upon the relatively inner sides of said wheels, and disposed upon the shaft between the wheels is a double clutch member 30 which is movable by 80 reverse sliding movements into engagement with said clutch members of the respective sprocket wheels. Journaled in the casing is a drive shaft 31 on which is a drive wheel 32 which may be driven by belt or chain 85 from an electric or other suitable motor, and fixed to this wheel is a sprocket pinion 33 connected by a drive chain 34 with a sprocket wheel 35 of larger diameter on a countershaft 36. On this countershaft are 90 sprocket pinions 37 and 38 which are connected with the sprocket wheels 28 and 29 by chains 39 and 40, one of said chains, chain 39, being crossed so that upon a continuous motion of the drive sprockets in 95 one direction the loose sprocket wheels 28 and 29 will be driven in opposite directions. The double clutch member 30 is provided with pins or trunnions which slidably and pivotally engage the arms of a yoke 41 pivoted to swing laterally in bearings 42 and which is coupled by a link or connecting rod 43 to one arm of a bell crank lever 44, the other arm of which is connected with a longitudinally movable reversing bar or 100 rod 45 connected at its opposite ends with pivoted trip arms or levers 46 and 47 adapted to be respectively engaged and operated by contacts 46' and 47' on the carriage for shifting said bar in opposite directions to 105 reverse the direction of motion of the carriage. When the arm 47 is tripped to move the reversing bar toward the right hand end of the casing the clutch 30 will be engaged with the gear 28 to feed the carriage forward, while when the trip arm 46 is operated to shift the bar toward the left hand end of the casing the clutch 30 will be engaged with the gear 29 to move the carriage rearwardly or on its return motion. 110

The reversing bar is connected to the inner end of a pair of toggle locking links 48, which are connected at their outer ends with the free ends of plate springs 49 fastened 5 at their opposite ends to a supporting bracket 50 and engaged by a yoke 51 having its arms threaded to receive retaining nuts 52, said yoke serving as a limitation device to restrict the spread of said arms and as a 10 tensioning device whereby the spring action of the arms may be controlled. These springs serve to lock the toggle locking links beyond center in either direction of movement thereof to hold the bar and clutch 30 15 in their different positions against casual movement out of such positions, the springs and links serving to control both the reversing bar and its trip arms and the double clutch in this respect, as will be readily understood. Thus when the bar is moved with the clutch in either direction to shift the direction of motion of the carriage the parts will be positively maintained in thrown position until again reversed by the action of 20 25 the carriage.

In the operation of the device, the construction of which will be readily understood from the foregoing description, taken in connection with the drawings, the rear sign carrier frame of the stack in the compartment 7 will be engaged by the rear dog of the carriage and moved forwardly behind the stack in the compartment 6, at the same time that the front sign carrier frame 30 35 which has been displayed through the opening 5 at the front of the compartment 6 will be engaged by the other dog and moved backward on its return motion into the front of the compartment 7, these springs 14 and 40 45 in said compartments operate to permit the feeding in and out of the frames while maintaining the same in stack formation and pressing the advance frame of each stack into alignment with the respective guideways. Hence at the limit of working 50 55 movement of the carriage a sign will be moved forward in the chamber 6 for display, and on the return motion of the carriage the sign which has been on display will be moved rearwardly into the compartment 7, the new sign being maintained in display position until the carriage on its ensuing feed motion brings another frame from the rear of the compartment 7 into 60 65 the rear of the compartment 6 and on its backward motion moves the displayed sign out of display position. It will thus be evident that the signs will be intermittently fed forward and displayed for predetermined periods, which may be of any desired duration, so that any desired number of display signs may be brought into display position

within a given period. It will further be evident that the construction for obtaining the desired result is simple, and yet reliable 65 and efficient in character, of an inexpensive type, and not liable to easily get out of order. While the construction disclosed is preferred, it will of course be understood that the invention may be modified within 70 the scope of the appended claims, without departing from the spirit or sacrificing any of the advantages thereof.

I claim:

1. In combination with a reciprocating carriage provided with a rack bar, transmission gearing including a pinion meshing with said rack bar and sets of gear elements for alternately reversing the direction of motion of said pinion, a clutch device for 80 alternately throwing said sets of gear elements into and out of action, a longitudinally movable swinging bar for actuating said clutch device, swinging trip members connected with the bar, coöperating trip elements upon the carriage for alternately actuating said trip members, toggle locking links movable into and out of locking engagement with the bar and operative on reverse movements of said bar for engaging 90 and holding the same in thrown position, and spring supports for said toggle locking links acting to hold the same secured in reversed working positions.

2. In combination, a reciprocating carriage provided with a rack bar, driven gearing including a pinion meshing with said rack bar for reciprocating the carriage, primary drive gearing, and reversing and transmission gearing between said primary 100 drive gearing and the driven gearing for driving the latter in opposite directions, said reversing and transmission gearing comprising a pair of oppositely rotatable actuating elements, a clutch device for alternately shifting said elements into and out of action, a longitudinally movable swinging bar for actuating said clutch device, swinging trip members connected with the bar, coöperating trip elements upon the carriage for alternately actuating said trip members, toggle locking links movable into and out of locking engagement with the bar and operative on reverse movements of said bar for engaging and holding the same in 110 thrown position, and spring supports for said toggle locking links acting to hold the same secured in reverse working positions.

In testimony whereof I affix my signature in presence of two witnesses.

IANTHAS J. ROLFE.
